IRONING TABLE TOP

Donald J. Munson, Minneapolis, Minn., assignor to The J. R. Clark Company, Spring Park, Minn., a corporation of Minnesota

Filed Apr. 28, 1958, Ser. No. 731,537

6 Claims. (Cl. 38—139)

This invention relates to ironing tables and is particularly directed to improvements in ironing table tops or boards.

In my application Serial No. 641,149, filed February 19, 1957, there is disclosed a novel top construction for ironing tables which allows the front end portion or nose of the normally tapered top to be expanded to convert the top to a condition where it has a constant width throughout its length. The present invention is a modification of the concept disclosed in that application.

The primary object of the present invention is to provide a new and improved top construction for ironing tables wherein a conventional shaped elongated top having a unitary top surface with a tapering nose is provided with means for expanding and contracting the ironing surface area provided by the nose.

Another object of the invention is to provide an ironing table top having wing sections mounted thereon for relative spreading and closing movement to convert the top between tapered and generally rectangular shapes and having a new and improved control means for so moving said wing sections.

With these and other objects in view the invention broadly comprises the providing of a conventional shaped ironing table top having a tapered front end or nose portion with a pair of laterally opposing wing sections which are pivoted to the top for movement between a relatively closed position lying under the top nose portion and a relatively spread position on either side of the nose portion to give the top a constant width throughout its length, and a control member pivoted to the underside of the top and connected to the wing sections.

The above mentioned and additional objects of the invention will be brought to light during the course of the following specification, reference being made to the accompanying drawings, in which—

Fig. 1 is a plan view of the top with the nose wing section closed leaving the nose in tapered condition for normal ironing.

Fig. 2 is a plan view of the front end or nose portion of the top in expanded condition for use in ironing large pieces of flatwork or the like.

Fig. 3 is a left side elevation of the nose portion of the top in expanded condition.

Fig. 4 is an enlarged longitudinal vertical section through the control pivot housing taken on line 4—4 of Fig. 2.

Fig. 5 is a transverse vertical section through the top with the nose expanded and taken along line 5—5 of Fig. 3 and looking in the direction of the arrows.

Fig. 6 is an inverted plan view of the nose portion of the top in collapsed or normal operating condition.

Fig. 7 is an inverted plan view of the nose portion of the top in expanded condition as in Fig. 2.

Referring now more particularly to the drawings reference numerals will be used to denote like parts or structural features in the different views. The top is denoted generally at 10. It comprises a frame made up of longi-

2

tudinal frame members 11 and transverse frame members 12 which support an elongated sheet 14 of sheet material, such as flattened expanded metal, which forms the ironing surface. A marginal flange, denoted generally at 15, extends peripherally around the sheet 14 and is preferably connected to the ends of the frame members to provide a rigid unitary top structure. The top is, of course, supported by a suitable understructure such as a pair of leg frames connected to the frame for erecting and collapsing operation. Inasmuch as such top supporting structure forms no part of the present invention, it is not shown in the drawings.

The top has the usual forwardly tapering design with the flange 15 having portions 16 extending in parallel throughout the main portion of the top length and portions 17 which converge toward the front end of the top into an arcuate flange portion 18 forming a tapered nose. As thus far described the top has a conventional design.

A pair of wing sections mounted on the nose portion 20 of the top for laterally expanding and contracting that portion are each designated generally at 19. Each of these sections comprises an elongated longitudinally tapering piece of flat rigid sheet material 20 having a marginal flange 21 along one straight edge. The sections are mounted as shown in Fig. 1 with their broader ends lying in overlapping relation immediately under the sheet 14 and with the flanges 21 extending rearwardly along the flange portions 17. At the junction of the top flange portions 16 and 17 at each side of the top, the flange 15 is provided with a vertical slot 22 (Fig. 2). Flange 21 on each wing section 19 has a tongue 24 projecting rearwardly therefrom and inwardly through the slot 22 to provide a hinge connection between the top and wing section for moving the section 19 on a horizontal plane 35 about a vertical pivot connection at its rear end. Flange portions 17 on the top 10 are provided with elongated slits 25 which extend along the flange immediately below the plane of the sheet 14 as shown in Figs. 3 and 4. These slits extend the entire length of the sections 19 and the sheeting sections 20 extend therethrough along the underside of the sheet 14. While the front portions of the longitudinal ribs 11 are positioned to support the sheet 14 they are not connected thereto thus allowing the wing section sheets 20 to slide therebetween. Thus the two sections 19 are movable between the relatively closed and spread positions shown respectively in Figs. 1 and 2, with the sheets 20 of sections 19 in each case lying just under sheet 14 to present a substantially continuous surface therewith when lying in their spread or outer positions. A guide plate 26 is mounted across the leading ends of members 11 to guide the wings in their inward and outward movement.

A control means for operating the wing sections between their spread and closed positions is provided and will now be described in detail. A tray-shaped shield member 27 is mounted under the nose portion of the top with its lateral and front edges secured to the flange portions 17 and 18. The side walls of the shield are provided with longitudinally extending slots 28. An elongated control handle 29 is pivoted on top of the shield 27 as by a rivet at 30 for swinging movement about a vertical axis. The shield is provided with an arcuate slot 31 formed about the axis of pivot 30. The control extends in opposite directions from the pivot 30 with an extended portion 32 extending through the slot 31 and carrying a knob 34 at its end. A pair of rigid links 35 have their inner ends pivoted to the control 29 at points which are diametrically opposed and equally spaced with respect to the pivot axis 30 and their outer ends pivoted to the flanges 21 on the wing sections 19, the links extending laterally through slots 28.

The inner edges of the wing top sheets 20 may be curled slightly in opposite directions as at 36 to prohibit edge to edge contact when the sections are closed and enabling the sheets to smoothly slide one over the other. The front edges 37 of the sections are preferably formed with a smoothly curved design eliminating any sharp corners to prohibit damage to any pad used to cover the top in its expanded condition.

Operation of the invention will be readily understood. During performance of the normal ironing operations the nose of the top will be contracted as in Figs. 1 and 6 with the wing section surface pieces lying in closed overlapping position in contiguous relation under the nose portion of sheet 14. The flanges 21 will rest against flange portions 17 of the top 10. In this condition the top, of course, has a forward endwise taper and is shaped in the manner of a conventional top.

When the operator desires to expand the nose for flat-work ironing she merely pulls the knob 34 swinging the lever in its arc of movement about the pivot 30 to the position shown in Fig. 7. This, of course, places links 35 under compression causing the wing sections to be pulled outwardly through slits 25 in a relatively spreading movement about their rear end pivotal connections. When the control 29 engages the end of slot 31 the sections will be fully spread with the flanges 21 in longitudinal alignment with the rim portions 16. Inasmuch as the sheeting sections 20 lie immediately below the sheet 14 they will in effect form lateral extensions to the ironing surface of the top nose portion and give the overall ironing surface a rectangular shape.

Conversely, to close the sections 19 the control is swung in a return direction on its pivot and links 35 will be placed under tension pulling the sections 19 into the lateral limits of the top nose portion with flanges 21 resting against the rim portions 17.

It will be appreciated that the top is readily adapted for use with a table pad having an expandable end portion for covering the front or nose end.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. An ironing table top structure comprising an elongated unitary top member having a body portion with parallel side edges and a nose portion extending integrally from one end of the body portion and having converging side edges, an elongated side wing member extending longitudinally along one side of the nose portion with the wing member and nose portion complementarily providing a generally flat ironing surface and the longitudinal side edge of the wing member remote from the nose portion being straight and disposed in longitudinal alignment with the adjacent side edge of the body portion, means movably mounting the wing member on the top member for inward movement of the wing member in a plane generally parallel to the plane of the ironing surface into overlapping relation with respect to the nose portion so as to provide for a contracted end ironing surface, and said nose portion extending endwise from the body portion a distance greater than the wing member.

2. An ironing table top structure comprising an elongated unitary top member having a body portion with parallel side edges and a nose portion extending integrally from one end of the body portion and having converging side edges, a pair of elongated side wing members extending longitudinally at opposite sides of the nose portion with the wing members and nose portion complementarily providing a generally flat ironing

surface which is equal in width to the body portion, means movably mounting the wing members on the top member for inward movement of the wing members in a plane generally parallel to the plane of the ironing surface into overlapping relation with respect to the nose portion so as to provide for a contracted end ironing surface, and said nose portion extending endwise from the body portion a distance greater than the wing members.

10 3. The subject matter of claim 2 wherein a single control member is rotatably mounted on the underside of the top for rotation on an axis perpendicular to the ironing surface, and means connecting the control member to both wing members for simultaneously moving such members inwardly as it is rotated on its axis.

4. In an ironing table top structure, an elongated top having a body portion and a tapered nose portion at its forward end, said top having a flat top ironing surface formed by flat metal sheeting, a pair of elongated wing

20 members disposed along opposite sides of the nose portion with their rear ends pivoted to the top on transversely spaced axes perpendicular to the ironing surface for movement of the wing members about said axes on planes parallel to said ironing surface between relatively

25 spread position lying beside the nose portion and a relatively closed position overlapping the nose portion, said wings having flat top surfaces and being mounted with said surfaces in contiguous relation to the underside of said sheeting to form extensions of said ironing surface when in spread position and to underlie said sheeting when in closed position, the length of the top forward of the pivot axes being greater than the length of the wing members forward of the pivot axes.

30 5. The subject matter of claim 4 wherein the top is provided with depending flange means extending along the end of the nose portion and in parallelism along the sides of the body portion, and each wing member having a straight depending flange along its outer edge

35 adapted to connect the nose portion and the adjacent body portion flange means when the wing members are in closed position and to lie in end to end alignment with said body portion flange means when the wing members are in spread position.

40 6. In an ironing table top structure, a top having a body portion and an end portion, said end portion being comprised of an integral extension of the body portion and a pair of side wings one at each side of the extension having top surfaces complementarily with the extension providing a generally flat ironing surface, means movably mounting said wings on the top for movement of the entire top surfaces thereof on planes generally parallel to the plane of the ironing surface into overlapping relation with respect to the extension

45 55 so as to provide for a contracted end ironing surface, a wing control member pivoted to the underside of the extension transversely intermediate the wings on an axis perpendicular to said surface, and rigid link means connecting the wings to diametrically opposing points on the control with respect to the control pivot axis.
